SEALING-IN METHOD FOR LAMPS AND
SIMILAR DEVICESPaul O. Cartun, Cleveland Heights, Ohio, assignor
to General Electric Company, a corporation of
New York

Application August 31, 1943, Serial No. 500,675

3 Claims. (Cl. 49—78)

1

This invention relates to the manufacture of devices having thermoplastic bulbs or envelopes, including electrical devices such as incandescent lamps and various kinds of discharge devices, which at present usually have vitreous envelopes. The invention aims at simplifying the manufacture of such devices, reducing their cost, and improving their structural characteristics, including the inlead seals where the current supply conductors pass through the envelope walls. The invention is especially adaptable and advantageous for rather small lamps and devices, and particularly very small glow lamps and lamps used for telephone switchboards. The invention is concerned with an operation corresponding to what in lamp manufacture is generally known as "sealing-in," and it is hereinafter explained with particular reference to its use in telephone lamps having incandescent filaments as their electric translation means.

The manufacture of small vitreous electrical devices such as telephone lamps presents special difficulties, since their smallness makes it impracticable to employ the usual "stem flare" type of construction generally used for lamps of ordinary sizes, in which the current leads to the filament or other electric translation means of the device and one or more auxiliary supports (if required) are fused into a sealed-up end of a hollow glass stem-tube whose other end is flared, and an exhaust tube (as it is termed) opens through the inlead seal, this assembly or "mount" being afterward fused and sealed into the neck of a glass bulb. In very small lamps, the "mount" is reduced to a mere pair of inlead wires joined by an insulative bead and interconnected by the filament; and sometimes even the bead may be omitted.

In the "butt-seal" type of construction, as it is called, the simplified mount just described is inserted into the bulb neck with its lead wires bent apart to extend outward across the end of the bulb neck wall, and a tube about as large as the bulb neck is "butted" endwise against the latter and fused thereto. This tube is used as an exhaust tube and is afterward sealed off to form an end closure for the bulb; and the radially projecting lead wires are bent to extend parallel with the bulb axis and thus facilitate basing the lamp.

In other suggested types of construction, an exhaust tube smaller than the bulb is inserted into the bulb neck between the outward extending lead wires of the mount, and the bulb neck is fused around this tube and united with it.

2

One method proposed for thus uniting the bulb neck and tube is to pinch in the softened bulb neck to the less softened tube end by suitable clamps brought together around the neck; another proposed method is simply to fuse the bulb neck around and to the tube end, which may be enlarged to minimize the necessary contraction of the neck and may have the mount leads fused into the periphery of the enlargement. Various measures have been proposed to prevent the tube from contracting to the point of being closed up when the bulb neck is sealed to it, such as blowing air in through the tube at just the right moment, or inserting a pin into the tube to keep it open, or preliminarily enlarging the end of the tube sufficiently to obviate such closure.

However, all of these methods present drawbacks of one kind or another, which it is unnecessary to notice in detail, except to remark that the neck-pinchng, air-blowing, pin-inserting, or similar measures that have been proposed to prevent closing up the exhaust tube all entail extra operations, which must be timed with some nicety in order to be successful.

In contrast with the methods above described, I have found that it is possible to fuse and seal an exhaust tube into a bulb neck by externally heating the bulb neck and allowing it to contract and coalesce spontaneously with the exhaust tube end extending into it—provided always that the heat is suitably applied, as explained hereinafter—without any of the special measures or complications above mentioned. Incident to this, a simple mount such as above mentioned may be sealed in with its lead wires extending parallel with the lamp axis out through the fused vitreous material forming the seal. When this last is done, the lead wires of the mount can be preliminarily attached to the tube end by fusing and embedding them sidewise in the vitreous material of the tube; or they can be preliminarily attached to the inside of the bulb neck in a somewhat similar way; or they may simply extend out loosely between the bulb neck wall and the smaller tube end within said neck, without any preliminary attachment to either part.

Various other features and advantages of the invention will appear from the following description of a species or mode of practice of the invention, and from the drawings.

In the drawings, Fig. 1 is an "exploded" tilted or perspective view of parts suitable for the fabrication of one type of electrical device according to this invention, in relations to one an-

other that indicate one preferred mode of assembly; Fig. 2 is a view of the parts assembled in proper relations for a sealing-in operation according to the invention, also showing somewhat diagrammatically a suitable form of apparatus for use in this operation; and Figs. 3 and 4 are top and bottom plan views of the beginning and end of the sealing-in operation, only the lamp parts and the gas burners and flames being shown.

Figs. 5 and 6 are side views of a lamp device after sealing-in according to the invention, Fig. 5 being taken parallel with the plane of the lead wires, and Fig. 6 at right angles to this plane; and Fig. 7 is a side view of a completed lamp after exhausting and sealing or tipping off.

Fig. 1 is a sort of a "exploded" view of component parts suitable for the fabrication of a small switchboard lamp in accordance with my invention: viz., a bulb or bulb blank 10 consisting of a short length of soft glass tubing with a hemispherical closed end 11, and with a mouth or neck portion 12 at its other end which is here shown unreduced and of the same size as the rest of said bulb blank, though this is not essential; an exhaust tube or tubulature 13 consisting of a plain, straight length of soft glass tubing; and a mount M shown as consisting of in-lead wires 15, 15 fused into opposite sides of an interconnecting insulative flattened glass bead 16, with a tungsten filament 17 connected between the inner ends of the lead wires. As here shown, the portions of the lead wires 15, 15 at the filament side of the bead 16 are straight and parallel, while the portions at the other side of said bead are offset and spread apart at 18, some distance from the bead, as well as at 19 close to it. In Fig. 1, the parallel outer portions of the leads 15, 15 beyond the offsets 18, 18 are shown so spaced apart as to admit the tube 13 between them with its end against said offsets, and the tube 13 and mount M thus assembled are shown just below and aligned with the bulb neck 12, ready for introduction into the bulb 10. However, it will be understood that the mount M might first be inserted into the bulb 10 by itself, and the tube 13 then inserted endwise into the bulb neck 12 between the outer lead portions.

As illustrative of the smallness of the parts for a switchboard lamp, it may be mentioned that the bulb blank 10 in Fig. 1 may consist of a 1-inch length of soft glass tube $\frac{1}{4}$ inch in external diameter, with a bore of about $\frac{3}{16}$ inch; the tube 13 may consist of a $4\frac{3}{8}$ inch length of soft glass tube $\frac{1}{8}$ inch in external diameter, with a bore of rather more than $\frac{1}{16}$ inch; the lead wires 15, 15 may be $1\frac{7}{16}$ inch lengths of "dumet" wire of 10 mil size, with their inner portions a little over $\frac{1}{16}$ inch apart; and the bead 16 may have a major dimension of about $\frac{1}{8}$ inch parallel with the plane of the wires 15, 15. Of course these dimensions and materials are illustrative merely: for example, iron lead wires 15, 15 might be used, with a suitable special glass for the parts 10, 13; and the invention might be used in making lamps of much larger size than switchboard lamps.

Fig. 2 shows the parts 10, 13, M assembled in proper relations ready for sealing in. The bulb-blank 10 is shown as held vertical in an upper "chuck" device 20 comprising some five spring fingers 21 formed by longitudinal slits in the wall of a resilient metal tube of suitable bore, while the tube 13 is shown as held vertical in a lower hollow upright spindle 22 in axial alignment with

the device 20. The mount M is shown straddled on the upper end of the tube 13, with the lower portions of its leads 15, 15 held loosely in corresponding longitudinal holes 23, 23 in the end of the spindle 21, at opposite sides of its axial bore for the tube 13 and parallel therewith. The upper end of the tube 13 extends into the open lower neck end of the bulb 10, while the lead wires 15, 15 extend downward between these parts and along the tube 13, diametrically opposite one another. A distance about equal to its own diameter is suitable for the tube 13 to extend within the bulb neck 12.

I have found that by externally heating the bulb neck 12 in a suitable manner, it can be softened and caused to contract or shrink spontaneously into internal contact with the tube 13, and the tube can be softened so as to coalesce spontaneously with the softened bulb neck, while closing up of the tube opening or bore can be forestalled and prevented by substantially stopping the application of heat promptly, before the unified parts can contract sufficiently to close the tube opening. For this it is necessary to keep down or reduce the application of heat when the softened bulb neck 12 shrinks into contact with the end of the tube 13, so that the latter is only softened to coalesce with the former rather gradually, instead of being softened so rapidly or to such a degree that the united parts rapidly contract and close up the tube bore before the contraction can be stopped by the quick cooling that ensues when the heating is stopped.

The regulation and variation of the heating as just indicated can be brought about automatically by directing one or more external heating flames 25 tangentially of the bulb neck as shown in Fig. 2 preferably rotating the flame and the bulb relative to one another so as to heat the neck evenly and uniformly all around. A good arrangement for this purpose which is shown in Fig. 2 consists of a pair of gas burners 26, 26 aimed oppositely but out of line so that their slender "rat-tail" flames 25, 25 play parallel with one another tangentially and crosswise of the neck 12 at either side thereof, initially touching the unreduced neck as shown in Fig. 3. As shown, each burner 26 has three small, parallel, horizontal flames 25 lying in a vertical row one above another, so that they heat the bulb neck 12 over a substantial vertical width. With these flames suitably proportioned and aimed, they initially heat up and fuse or soften the neck 12 rather quickly so that it spontaneously contracts around the tube 13 and the lead wires 15, 15, which are thus embedded in the fused glass of the neck. As the neck 12 contracts in this way, it also draws inward away from and out of the heating flame(s) 25 as shown in Fig. 4, thus automatically reducing the application of heat to said neck 12 while the tube 13 is softening under the heat imparted thereto from or through the softened neck, and the parts are coalescing into a unified fused joint 27 as shown in Figs. 5 and 6. If the flames 25, 25 are kept small and are so aimed and spaced apart that they play nearly tangentially on the neck 12 before it begins to contract, as in Fig. 3, then the mere drawing away of the neck 12 out of the flames, as shown in Fig. 4, when it contracts reduces the application of heat sufficiently; so that it is generally unnecessary to shift or reduce the flames themselves during the operation.

When the parts 12, 13 coalesce to form the joint 27, the application of heat thereto from the flames

25, 25 is virtually or substantially stopped, as by moving the burners 26, 26 aside out of range of the joint, or by quickly turning down the flames so that they at most afford no more than an annealing heat while the joint cools off. Even though the tube opening or bore may contract to a somewhat reduced throat in the joint 27, as shown at 28, this is of no practical consequence in view of the small internal volume of the bulb 10. The joint 27 is, of course, smaller in external size than the unreduced part of the neck 12 and of the bulb 10, though larger than the tube 13. Owing to the presence of the lead wires 15, 15, which hold the glass and prevent it from contracting uniformly all around, the joint 27 is of an elongated or oval cross-section, rather than truly circular—as sufficiently appears from Figs. 4, 5, and 6.

While either the burners 26, 26 or the chuck and spindle 20, 22 might rotate to equalize the heating of the parts 12, 13 all around, it is generally simpler, perhaps, to rotate the chuck and spindle. For this purpose, they are shown in Fig. 2 as interconnected to revolve together by toothed gearing 29, 29 and an upright shaft 30. The shaft 30 (and through it the parts 20, 22) may be driven at constant speed by any suitable means, not shown.

After completion of the sealing in operation as shown in Figs. 5 and 6, the lamp may be exhausted through the tube 13 in the usual way and then sealed or tipped off close as shown at 33 in Fig. 7, thus completing it ready for basing.

Besides the extreme simplicity of the operations involved in its manufacture as described, the device as shown in Figs. 5, 6, and 7 offers the advantage that its leads 15, 15 naturally extend in the direction of the bulb axis and within the limits of its cross-sectional area as axially projected, instead of extending out radially as in the butt-seal type of construction above mentioned. This simplifies the operations involved in basing the device. It also obviates any bending of the leads 15, 15 just outside their seals in the glass, which is necessary with the butt seal construction, and often results in damaging the seals so that they develop leaks. In addition, the extent of embedding glass 27 along the leads 15, 15 is greater, giving greater assurance of gas-and-vacuum-tight lead seals, and obviating risk of short-circuiting a lamp in basing by contact of both leads 15, 15 with a base shell (not shown).

What I claim as new and desire to secure by Letters Patent of the United States is:

1. The method of making a seal of the class described which comprises assembling the end

5 of a glass exhaust tube within an outer tubular glass member with lead-in wires extending longitudinally therebetween, rotating the assembly about its axis, directing a heating flame substantially tangentially of the outer member and maintaining the flame in its original position to cause the said outer member to soften and contract away from the flame to a predetermined extent and become fused to the exhaust tube whereby to seal portions of the lead-in wires in the resulting joint without closing up the exhaust tube.

10 2. The method of uniting lamp parts which comprises assembling an end of a glass exhaust tube within the tubular neck of a glass bulb with lead-in wires extending longitudinally therebetween, rotating the assembly about its axis, directing a heating flame substantially tangentially of said bulb neck and maintaining the flame in its original position to cause said bulb neck to soften and contract away from the flame to a predetermined extent and become fused to the exhaust tube whereby to seal portions of the lead-in wires in the resulting joint without closing up the exhaust tube.

15 25 3. The method of uniting parts for lamps and similar devices which comprises assembling an end of a glass exhaust tube within an outer tubular glass member with leading-in wires extending longitudinally therebetween, and directing a flame at the said assembly while rotating the flame and said assembly relative to one another, said flame being of slender proportions and aimed in a direction substantially tangential to the original peripheral outline of said outer glass member and maintaining said flame in said direction until said outer glass member is softened and contracts away from the flame to a predetermined extent and becomes fused to the exhaust tube and seals portions of the leading-in wires in the resulting joint without closing up the exhaust tube.
